(57) **CLAIM**

The ornamental design for a shower head, as shown and described.

DESCRIPTION

FIG. 1 is a bottom plan view of a shower head, showing my new design;

FIG. 2 is a left side elevational view thereof, the right side being a mirror image;

FIG. 3 is a top plan view thereof;

FIG. 4 is a front elevational view thereof;

FIG. 5 is a perspective view thereof, from the bottom, left side and front; and,

FIG. 6 is a perspective view thereof, from the top, right side and front.

The shower head has an extremely reduced thickness, compared to the thickness of shower heads available in the prior art.
